SPATULA OR THE LIKE

Hoyt K. Foster, Hollis, N.Y., assignor to S. W. Farber,
Inc., New York, N.Y., a corporation of New York

Filed July 6, 1962, Ser. No. 70,817

Term of patent 14 years

(Cl. D44—29)

FIG. 1

FIG. 3

FIG. 1 is a perspective view of a spatula showing my new design;

FIG. 2 is a plan view of the spatula;

FIG. 3 is a side elevation of the spatula.

The characteristic feature of the design resides in the parallel single tines lying in the same plane being vertically offset from the angularly disposed handle of matching stock, all as shown.

I claim:

The ornamental design for a spatula or the like, substantially as shown and described.
